UNITED STATES PATENT OFFICE.

CULLEN H. JAMES, OF LOS ANGELES, CALIFORNIA.

DESIGN FOR A CAN.

SPECIFICATION forming part of Design No. 25,665, dated June 23, 1896.

Application filed October 21, 1895. Serial No. 566,417. Term of patent 14 years.

To all whom it may concern:

Be it known that I, CULLEN H. JAMES, a citizen of the United States, residing at Los Angeles, in the county of Los Angeles and State of California, have invented and produced a new and useful Design for Cans, of which the following is a specification, reference being had to the accompanying drawings, in which—

Figure 1 is a perspective view of a can embodying my design. Fig. 2 is a vertical mid-section of the same.

The design for the can comprises a vertical body 1, a horizontal top 2, a sloping bottom 3, sloping toward the front of the can, and bead ornamentation in the body of the

can, consisting of two upper bands $a a'$, arranged in horizontal planes parallel with the top of the can-body, and two forwardly-sloping lower bands $a'' a'''$, arranged in oblique planes parallel with the sloping bottom. 20

The characteristic features of the particular design for the can are the upright body and the sloping bottom.

What I claim is—

The design for a can substantially as set forth. 25

CULLEN H. JAMES.
